UNITED STATES PATENT OFFICE.

HUGH F. LATIMER, OF HYATTSVILLE, MARYLAND.

WINDOW-SCREEN.

1,110,500.

Specification of Letters Patent. Patented Sept. 15, 1914.

Application filed March 31, 1910. Serial No. 552,598.

To all whom it may concern:

Be it known that I, HUGH F. LATIMER, a citizen of the United States, residing at Hyattsville, in the county of Prince Georges, 5 and State of Maryland, have invented certain new and useful Improvements in Window-Screens, of which the following is a specification.

My invention relates to improvements in 10 window-screens and fittings therefor.

The object of my invention is to provide means whereby a window may be covered to its full extent with screening, while at the same time such screen is so arranged as 15 to allow the lower half to be raised and lowered to permit access to the window or to the outside blinds.

A further object of my invention is to provide a set of fittings for screens to be 20 hung as above indicated, whereby such fittings may be made and sold as hardware specialties and may be fitted to any suitable screen.

With the above general object in view my 25 invention consists in the features, details of construction and combination of parts which will first be described in connection with the accompanying drawings, and then particularly pointed out in the claims.

30 In the drawings: Figure 1 is a perspective view of a window provided with an outside screen embodying my invention; Fig. 2 is a sectional view of the same; Fig. 3 is a perspective view of one of the hanger rods 35 employed in this construction; Fig. 4 is a detail sectional view showing the meeting edges of the upper and lower screens; Fig. 5 is a front elevation of a window provided with an inside screen embodying a modified 40 form of my invention; Fig. 6 is a sectional view of the same; Figs. 7, 8 and 9 are detail elevations of a modified form of hanger device in different position; Fig. 10 is an enlarged detail view, partly in section, of said 45 hanger device; Fig. 11 is a section of the meeting rails of an upper and lower screen showing one form of locking mechanism employed by me; Fig. 12 is a front elevation of the same; and Fig. 13 is a perspective 50 view of the latch striker plate.

Referring to the drawings, A is a window frame, and B and C are the upper and lower window sashes respectively. All this part of the construction is old and well known 55 and needs no especial description.

D is a lower window screen arranged in a suitable manner to slide vertically in the window frame, as, for example, by providing guiding strips in the usual way, one of which is shown at d in Fig. 1. The upper screen is indicated at E and normally rests in the same vertical plane with the lower screen. The upper screen is supported in a manner to permit it to move outward when the lower screen is moved upward, 60 whereby when the lower screen is raised to its full extent it is behind the upper screen. In order to support the upper screen and yet allow this displacement of the upper screen, a suitable supporting means is provided. In the construction shown, for example, in Figs. 1 and 2 this supporting means comprises two rods, F and G, each having both of its ends cranked as indicated in the drawings, the said rods being 65 journaled in suitable bearings on the upper screen and having their ends inserted in sockets in the window frame. In the example shown these sockets may be merely 70 holes bored in the casing, into which the 75 ends of the rods are inserted by slightly bending or arching the rods, whose resiliency will permit this to be done.

In order to permit the upper screen to rise slightly upward as it swings outward, 80 a clearance space must be provided between the top of the said upper screen and the under surface of the upper part of the window frame, and this clearance space is obtained by terminating the upper screen 85 slightly short of the top of the window frame and filling the space in the plane normally occupied by the screen with a strip H. 90

In order that the upper screen may move automatically out of the plane of the lower screen by the mere act of lifting the lower screen the meeting edges of the two screens and the meeting edges of the upper screen and the strip H are suitably formed so that upward movement of the screens causes a 95 displacement of the upper screen in the desired direction. This may be done by beveling the said meeting edges as indicated in the drawings, or if desired by securing to the edges beveled or rounded 100 strips. In Fig. 4 the upper edge of the lower screen is shown provided with such a separated rounded strip, indicated at I.

The operation of the device is as follows: 105 When the lower screen is lifted, the beveled

meeting edges of the upper and lower screens cause the upper screen to move outward from the window sash, the cranked arms of the rods F and G causing the said upper screen to move in parallelism with the window sash. The continued upward movement of the lower screen causes it to pass behind the upper screen, thereby giving access to the window sashes or to the outside blinds. Upon pulling down the lower screen to its normal position the upper screen will drop into place by its own weight.

In the construction shown in Figs. 5 and 6 the upper screen is hung at the upper end only, the lower end of the upper screen being normally locked to the upper end of the lower screen by any suitable locking means. The locking device is placed on that side of the screens which is to be toward the inside of the house. Figs. 5 and 6 show an arrangement where the screens are assumed to be on the inside of the window, the latch plate K of the locking device being attached to the bottom rail of the upper screen. Figs. 11 and 12 illustrate an arrangement of locking means where the screens are to be on the outside of the window. In the example shown, the locking means comprises a flat plate K fastened to the top rail of the lower screen, which is recessed behind the plate to accommodate a swinging latch lever k pivoted to the plate and having one end arranged to enter an opening k' in a striker plate K' fastened to the lower edge of the upper screen, the other end of the lever being bent outward to form a handle k². When the lower screen is to be raised, the latch lever is swung to withdraw its latching end from the opening in the striker plate and below the beveled upper edge of the lower screen. The lower screen may then be raised, the upper screen being swung outwardly. When the screens are to be inside the window, it is ordinarily best to invert the arrangement of the described parts of the latching device, this being indicated in Fig. 5.

In the modification shown in Figs. 5 and 6, the upper screen is not supported by a rod extending entirely across the screen, but by a pair of hangers, each consisting of a link L having its ends cranked in opposite directions, as shown in Fig. 7, one of said ends having a head as indicated at l. To the head of the window frame is secured a top-hanger plate M having a journal bearing m in which the headed end of the hanger L is rotatable. To the upper screen frame is secured a lower hanger plate N which also is provided with a journal bearing for the unheaded arm of the hanger L. By this arrangement, the upper screen is free to swing upward and away from the normal position, 65 as the lower screen rises.

In order to allow of the convenient removal of the upper screen, the hanger devices may be made so that the hanger L may be removed from one of the journal bearings on each side, and this constitutes an important feature of my invention. In its specific preferred form, the journal bearings of the top hanger-plates M are slotted, as indicated in Fig. 10 and the headed arm of the hanger L is flattened in cross-section so that when it is rotated in the bearing to the position shown in Fig. 10 it may be slipped out of the said journal bearing, but at any other position its diameter is too great to allow it to pass through the slot. Furthermore, the position when the minimum diameter of the arm coincides with the slot is such that the upper screen would never reach such position in the normal operation of the screens, so that there is no danger of the hangers L being separated from their top hanger plates by accident.

In order to prevent any danger of the upper screen being shaken by the wind and thereby rattling, a suitable light spring pressure may be maintained on the upper screen, for example by having a coiled spring P with one arm p secured to the frame and the other arm p' arranged to bear on the vertical part of the hanger as indicated in Fig. 5.

Having thus described my invention what I claim is:

1. The combination, with a window frame, a lower screen, and means for guiding the lower screen vertically in the window frame, of an upper screen arranged to lie normally in the same plane with the lower screen and means for hanging the upper screen to the frame in a manner to allow it to be displaced out of the path of the lower screen.

2. The combination, with a window frame, a lower screen, and means for guiding the lower screen vertically in the window frame, of an upper screen arranged to lie normally in the same plane with the lower screen and detachable means for hanging the upper screen to the frame in a manner to allow it to be displaced out of the path of the lower screen.

3. The combination, with a window frame, a lower screen, and means for guiding the lower screen vertically in the window frame, of an upper screen arranged to lie normally in the same plane with the lower screen, means for hanging the upper screen to the frame in a manner to allow it to be displaced out of the path of the lower screen, and means for locking the upper and lower screens together in their normal positions.

4. The combination, with a window frame, a lower screen, and means for guiding the lower screen vertically in the window frame, of an upper screen, arranged to lie normally in the same plane with the lower screen, journal bearing devices secured to the win-

dow frame, journal bearing devices secured to window screen, and hangers having their ends bent in opposite directions, one end of each hanger being inserted in a journal bearing device on the screen and the other end in a journal bearing device in the window frame.

In testimony whereof, I affix my signature in the presence of witnesses.

HUGH F. LATIMER.
